UNITED STATES PATENT OFFICE

2,500,639

DISCHARGE SPOUT FOR RESILIENT
WALLED DISPENSERSHerman B. Lerner, South Orange, N. J., assignor
to Celluplastic Corporation, Newark, N. J., a
corporation of New Jersey

Application November 27, 1946, Serial No. 712,512

1 Claim. (Cl. 222—215)

1
The object of this invention is to provide a dispenser which may be made of transparent, plastic material, which is light in weight, is adapted to be accurately manually manipulated for the controlled discharge of the contents in small, measured quantities, and which is efficient and durable in use.

A further object of the invention is to provide a dispenser so constructed that it may be rapidly manufactured in large quantities by the use of suitable machinery.

A further object of the invention is to provide a dispenser of novel structural features such as will appear more particularly from the description hereinafter.

In the drawings,

Fig. 1 is a vertical, sectional view of a cap member adapted to be used in connection with the dispenser of my invention.

Fig. 2 is a vertical, sectional view of the spout member thereof.

Fig. 3 is a vertical, sectional view, partly fragmentary, showing the spout member affixed to the body member of the dispenser.

Fig. 4 is an elevational view of a dispenser embodying my invention, with the cap affixed thereto, and

Fig. 5 is a similar view, with the cap removed, showing the manner in which the dispenser may be manually compressed for the measured discharge of the contents thereof.

As shown in the drawings, the dispenser 10 embodying my invention comprises a body member which is preferably made of cellulose acetate or of a similar plastic material, light in weight, preferably transparent or translucent, and possessing a high degree of elasticity throughout its length.

The dispenser body comprises an elongated tubular member 11 of thin-walled construction, which is highly flexible throughout its length and is maintained rigid at its opposite ends A, B. The member 11 is closed at one end 12, said closed end having a medially concave portion to define a rigid rim 14 to impart stiffness to said end 12. The end 12 of the body member 11, may, instead of having the recessed portion 13 defining the rigid rim 14, be thickened or otherwise deformed or fabricated for the purpose of making the same relatively rigid.

The spout 16 of the dispenser is provided with a flared shoulder 17 having a circumferentially recessed portion 18 adapted to register with and be fixed to the open upper end 15 of the member 11, as by cementing the same thereto as at 19, or by the use of any of the other sealing expedi-

ents well known to those skilled in this art. The spout member 16 may be made of the same material as the member 11 or may be made of a material having different characteristics, if desired. 5 The spout member is preferably substantially rigid, being made of substantially thicker and less yielding cross-section than the tubular member 11, so as to rigidly hold the upper end of said tubular member thereto. The tubular body member 11 is thus rigidly held at opposite ends A and B thereof, while the thin-walled, elongated construction thereof throughout its length renders the same highly elastic and subject to ready compression manually, as hereinafter more fully explained.

The spout 16 is provided with a longitudinal medial aperture 20 which is tapered toward the end 21 of said spout remote from the shoulder 17 so that, at the discharge end of said spout, the aperture will be of relatively small size. The spout is further provided with an externally threaded portion 22 adapted to be threadedly engaged by the internally threaded portion of the cap 23 to seal the dispenser. In addition, the spout 16 is provided with a non-circular flange 25 integrally extending therefrom but spaced from the closure 17 a sufficient distance to provide a finger receiving and cooperating area, while there is a similar non-circular flange 26 on the cap 23 to provide a second finger cooperating area. By holding the flange 25 in the fingers of one hand and the flange 26 in the fingers of the other hand, the cap may be readily removed and replaced as needed, even though the outer surface may otherwise be too slippery to grip securely.

In manufacturing the device, the body member 11 is initially filled with the product to be dispensed, and then the spout 16 is affixed thereto, as above described, closing the same. The cap 23 is threaded onto the spout, effectively sealing the same. The cap may be readily removed therefrom when it is desired to discharge the contents of the dispenser. At such time, the dispenser may be inverted as shown in Fig. 5, and the thin walls 45 11 thereof manually compressed to discharge measured quantities of the contents. By virtue of the relatively small size of the aperture 21 at the end of spout 16, the contents of the dispenser, such as, for example, oil, will normally tend to remain within the dispenser and will be ejected therefrom only in measured quantities responsive to the compression of the walls 11 manually as indicated at 24. By this arrangement, it is possible to direct the spout aperture to the precise point at which oil or other contents of the dis-

dispenser are to be applied and to discharge the precise and measured quantity desired in a simple and effective manner. As the member 11 is preferably made of a transparent or translucent plastic material, it is possible at all times to observe the quantity of material within the dispenser, and the rate of discharge of material therefrom.

The cap 23 is preferably made of an opaque material or of a material distinctly colored from the material of the spout, so that the user may observe at a glance whether or not the cap is fixed to the dispenser. The spout 16, tubular member 11 and cap 23 may be molded or fabricated of plastic material by use of any of the methods conventional in the plastic industry or suitable for the purpose.

Having thus described my invention, what I claim as new and desire to secure by Letters Patent, is:

A dispenser for liquids comprising a tubular, resilient, cylindrical body member having a closed end and an open end, a hollow closure member for the open end of the body member, the said closure member having an annular shoulder at one end adapted to receive the open end of the body member and a discharge tip at the other end, the said shoulder having a hollow cylindrical apron depending therefrom, adapted to be received in the open end of the body member, the apron having a substantially smooth outer wall adapted to fit snugly in the open end of the body

member, the closure member being secured to the body member, a spout for the closure member integral therewith, said spout being uniformly and continuously tapered from the shoulder to the discharge tip, a finger cooperating non-circular flange extending from the outer tapered surface of said spout adjacent to but sufficiently spaced from the closure member shoulder to provide a finger receiving area, a uniformly tapered discharge passage in the spout extending therethrough, a threaded cylindrical sleeve on the spout portion located remotely from the tip, but between said finger cooperating flange and said tip, and a conical closure cap having an internally threaded, cylindrical open end adapted to threadedly engage the threaded cylindrical sleeve on the spout for enclosing the tip and a substantial length of the spout, and a non-circular flange integrally extending from the outer surface of the internally cylindrical open end of said cap to provide a second finger cooperating area.
